UNITED STATES PATENT OFFICE.

DAVID E. ROWLAND, OF CANTON, OHIO.

WRENCH.

No. 878,673.

Specification of Letters Patent.

Patented Feb. 11, 1908.

Application filed September 21, 1907. Serial No. 393,992.

To all whom it may concern:

Be it known that I, DAVID E. ROWLAND, a citizen of the United States, residing at Canton, in the county of Stark and State of Ohio, have invented certain new and useful Improvements in Wrenches; and I do hereby declare that the following is a full, clear, and exact description of the same, reference being had to the accompanying drawing, making a part of this specification, and to the numerals and figures of reference marked thereon, in which—

Figure 1 is a perspective view of all of the parts of the wrench properly connected. Fig. 2 is a perspective view of the detachable toothed-block removed. Fig. 3 is a perspective view of the wrench, showing the toothed-bar removed. Fig. 4 is a section of the wrench-head and detachable toothed-bar.

The present invention has relation to wrenches commonly known as alligator jaw wrenches, and it consists in the novel arrangement hereinafter described and particularly pointed out in the claims.

Similar numerals of reference indicate corresponding parts in all the figures of the drawing.

In the accompanying drawing, 1 represents the handle, which may be of the form shown, or it may be of any other desired form. The handle 1 is provided with the head 2, which head is provided with the jaws 3 and 4, which jaws are arranged substantially as shown and as shown they form a V shaped opening. The jaw 4 is provided with the socket 5 in which socket the toothed-bar 6 is inserted or placed as illustrated in Figs. 1 and 4. The outer end of the socket 5 is bounded by the inclined flange or shoulder 7, which inclined shoulder is for the purpose hereinafter described. The outer end of the toothed bar 6 is beveled, the inclination of the bevel corresponding with the inclination of the shoulder 7 and is so beveled for the purpose of providing a means for setting a portion of the tooth bar 6 under the inclined shoulder 7 as illustrated in Fig. 4, for the purpose hereinafter described.

Through the head 2 or just at the rear of the jaw 3 is located the screw 8, which screw is so located that its inner end will reach or be extended beyond the inner face of the jaw 3, near the junction of said jaw with the jaw 4. The inner end of the screw 8 is preferably beveled and is so beveled for the pur-

pose of providing suitable contact between the end of said screw and the inner beveled end of the toothed-bar 6.

A further object and purpose of beveling the end of the screw 8 and locating the screw at an angle to the toothed bar 6 is to provide a double wedge action upon said toothed bar; that is to say as the screw is moved toward the bar, the beveled end of the screw comes in contact with the beveled end of the toothed bar and forces the toothed bar endwise not only by the contact, but by a longitudinal movement of the screw as it moves down or upon the inclined end of said bar so that when the bar has been properly clamped between the inclined shoulder at the outer end of the socket and the beveled end of the screw, the back of the bar at the extreme beveled end will come under the beveled end of the screw thereby seating the cone end of the screw against the beveled end of the toothed bar, thereby preventing any relative movement as between the jaw and the toothed bar and the crowding of the toothed bar is at an angle to a longitudinal line with reference to the screw, so that the screw forms a double purpose, first to crowd the toothed bar endwise and second to set the beveled end of the screw in full contact with the beveled end of the toothed bar. The screw 8 is for the purpose of holding the toothed bar 6 in proper relationship with reference to the jaw 4, and at the same time locking said toothed-bar in the socket 5.

It will be understood that when the screw 8 is withdrawn so as to bring its inner end away from the toothed-bar 6 said toothed-bar can be lifted from its socket by an upward and rear or longitudinal movement, thereby freeing the outer end of the toothed bar 6 from under the inclined flange or shoulder 7, after which said toothed bar can be removed. It is well understood that in wrenches of this kind that the teeth formed upon the toothed bar 6 will become worn from continued and long use and when the teeth are formed integral with the jaw or jaws of a wrench of the alligator type, said teeth must be sharpened or the wrench as an entirety must be thrown away; but by providing the detachable toothed bar 6 a new bar can be substituted for a worn one, or if in the event a toothed bar becomes broken a new one can be substituted, thereby saving the expense of an entire new wrench.

It will be understood that as the screw 8 is

forced against the inner beveled end of the toothed bar said toothed bar will be crowded endwise and held in a firm position so that there can be no relative movement as between the toothed bar and the jaw. The toothed-bar 6 should be formed of such a size that its toothed face will be extended beyond the face of the jaw 4 so that the bar can be set upon the pipe or nut designed to be operated upon. In the drawings I have shown the opposite jaw from that to which the toothed bar is attached formed plain, owing to the fact that it is not of importance or necessary to form teeth upon the jaw opposite the toothed bar, owing to the fact that the toothed bar will prevent any slipping or sliding as between said toothed-bar and pipe or wrench upon which said toothed-bar is applied.

It will be understood that by forming the jaws as shown said jaws will be in position to properly grip nuts of different sizes by reason of the angularity of said jaws with reference to each other.

Having fully described my invention what I claim as new and desire to secure by Letters Patent, is—

1. As an improved article of manufacture, a wrench of the class described, consisting of a handle and a wrench-head, integral jaws extended from said head and located at an angle to each other, one of said jaws provided with a socket having a width less than the width of the jaw, said socket provided

with an inclined shoulder at its outer end, a 35 detachable tooth bar formed of a width to correspond with the width of the socket and provided with beveled ends, said toothed bar located in the socket and a screw located at an obtuse angle to the toothed bar and said 40 screw adapted to bear against the inner beveled end of the detachable toothed bar, substantially as and for the purpose specified.

2. As an improved article of manufacture, a wrench of the alligator type consisting of a 45 handle and a wrench-head, jaws located at an angle to each other, one of the jaws provided with a socket, said socket bounded at its outer end by an inclined ledge, a detachable toothed bar adapted to be located in the socket 50 and provided with beveled ends, one of the beveled ends adapted to be seated under the inclined ledge, a screw located in the wrench-head and at an obtuse angle to the detachable toothed bar and said screw provided with an 55 inner beveled end corresponding with the beveled end of the toothed bar adjacent the screw, said beveled end of the screw adapted to abut against the inner end of the toothed bar, substantially as and for the purpose 60 specified.

In testimony that I claim the above, I, have hereunto subscribed my name in the presence of two witnesses.

DAVID E. ROWLAND.
